ATTORNEYS

UNITED STATES PATENT OFFICE.

GEORGE W. STOUT, OF MERCHANTVILLE, NEW JERSEY.

PACKAGE TIE.

1,405,459.

Specification of Letters Patent.

Patented Feb. 7, 1922.

Original application filed December 30, 1915, Serial No. 69,408. Divided and this application filed June 11, 1917. Serial No. 173,930.

To all whom it may concern:

Be it known that I, GEORGE W. STOUT, a citizen of the United States, residing at Merchantville, county of Camden, State of New Jersey, have invented a new and useful 5 Package Tie, of which the following is a specification.

In a contemporaneously pending application filed by me December 30th, 1915, Serial No. 69,408, I have disclosed and described a novel form of package tie, which is adapted in conjunction with a cord or string to expeditiously, reliably and efficiently wrap or secure a bundle of letters, 10 newspapers or packages of any nature or when made in larger sizes to be effectively used in tying bales of cotton, hay or other bulky material.

My present invention is a division of the application aforesaid and relates particularly to a package tie having a solid plate or body made of any suitable material, such as fibre, metal, wood or other material possessing the requisite strength and rigidity, 20 although in practice I prefer to make said plate or body of vulcanized fibre, said body having an extension, handle or tail-piece, an eye therein for the reception of a knotted end of the tying cord and a novel arrangement of kerfs, so correlated with respect to the median line of said longitudinal extension or tail-piece, that the tying cord can be caused to readily interlock and engage with said kerfs and be looped or secured upon said extension or tail-piece in such a way, 30 that the bundle, package or article is efficiently tied and cannot be accidentally unfastened.

For the purpose of illustrating my invention, I have shown in the accompanying drawing one form thereof which is at present preferred by me, since the same will be found in practice to give satisfactory and reliable results, although it is to be understood that the various instrumentalities of 40 which my invention consists can be variously arranged and organized and that my invention is not limited to the precise arrangement and organization of these instrumentalities as herein shown and described.

Figure 1 represents a perspective view of a package tie embodying my invention and showing also the tying cord and a package secured thereby.

Figure 2 represents a plan view of the package tie in detached position.

Similar numerals of reference indicate corresponding parts in the figures.

Referring to the drawings,

1 designates my novel construction of 60 package tie, the same comprising the solid plate or body 2, which is preferably constructed of vulcanized fibre or similar material, said body being preferably of circular form, although in accordance with the broad 65 spirit of my invention the exterior contour thereof may be varied according to requirements.

3 designates a longitudinal extension or tail-piece which is arranged diametrically 70 with respect to said body or, in other words, so as to form an extension of the diameter of said body and on one side of the median line of said body I locate the oblique cuts, kerfs or slots 4 and 5, the slot 5 being the 75 nearer to said tail-piece or extension 3. Substantially opposite to the kerf 5, I locate the kerf 6, which also extends in an oblique direction to the median line of said body, the kerfs 4, 5 and 6 having nearly or substantially the same line of inclination, the kerf 5 extending in nearly a radial line.

7 designates a hole or eye eccentrically located in the body 2, through which is passed the tying cord 8 the latter having a 85 knot 9 therein. The manner of manipulating the tying cord will be apparent from Figure 1, the body of the tie being first laid on the top of the package or bundle, as seen therein. The free end of the cord 8 after 90 being wrapped, carried or looped a desired number of times around the package 10 has its free end at about the point 11 passed upwardly through the slot or kerf 4 thence over the top of the tie and thence downwardly through the kerf 5, thence under the tie and upwardly through the kerf 6 and lastly is looped or tied, as indicated at 13, around the extension, handle or tail-piece 3, said free end being looped in any desired 95 manner therearound.

I preferably construct the sides of said extension, handle or tail-piece 3 with inwardly converging walls 12 so that the looped or knotted portion 13 will not readily 100 slip off or be disengaged therefrom.

It will be evident that my novel tie can be used in conjunction with a tying cord in other ways than that shown, without departing from the spirit of my invention. 110 To untie the package or handle it is only necessary to disengage the loop or knot 13

and then exert a pull on the cord in the proper direction, as is evident.

I am aware that it has been heretofore proposed in British Patent No. 4,056, of 5 1897, to employ a ring-like member having slots and eyes therein in conjunction with a handle having parallel sides but my invention is differentiated therefrom by reason of the employment of the handle or extension 10 3 having inwardly converging walls and by reason of the novel collocation of slots or kerfs with respect to the solid plate or body portion, which I employ, and to the aforesaid construction, I herein make no claim.

15 It will now be apparent that I have devised a novel and useful construction of a package tie which embodies the features of advantage enumerated as desirable in the statement of the invention and the above 20 description, and while I have, in the present instance, shown and described a preferred embodiment thereof which will be found in practice to give satisfactory and reliable results, it is to be understood that the same 25 is susceptible of modification in various particulars without departing from the spirit or scope of the invention or sacrificing any of its advantages.

Having thus described my invention what I claim as new and desire to secure by Letters Patent, is:—

In a package tie, a body portion, comprising a plate having an extension 3 projecting diametrically therefrom and provided with inwardly converging side walls 35 12, an eye 7 eccentrically located in said body at one side of a median line thereof, passing through said extension, and a slot 6 on the same side of said body as said eye positioned intermediately of said eye and 40 said extension and extending inwardly at an oblique angle to said median line, and terminating at a point intermediate said eye and extension, said body having on its opposite side two slots 4 and 5 extending thereinto on a line oblique to said median line, said slot 5 extending substantially radially into said body, and all of said slots being substantially parallel with each other and extending into said body at substantially 50 the same angle to said median line.

GEORGE W. STOUT.
